UNITED STATES PATENT OFFICE.

E ANDERS CHATTSTROM, OF DAVENPORT, IOWA.

DITCHING-MACHINE.

1,374,488.

Specification of Letters Patent. Patented Apr. 12, 1921.

Application filed May 29, 1919. Serial No. 300,750.

To all whom it may concern:

Be it known that I, E ANDERS CHATTSTROM, a citizen of the United States, residing at Davenport, in the county of Scott and 5 State of Iowa, have invented certain new and useful Improvements in Ditching-Machines, of which the following is a specification.

My invention has reference to ditching machines, and has for its chief purpose the formation of a trench of desired width and depth, in which may be laid the foundation of a building or other structure. The machine comprises a portable frame, carrying 10 earth excavating devices which are vertically adjustable and earth cutting mechanism, adapted for use in advance of the excavating devices, and also capable of being adjusted vertically. It is also provided with 15 means for elevating the excavated material and discharging the same at the side of the machine.

The motive power for transportation of the machine may be furnished by a tractor 20 or traction engine, and the operating parts of the machine can be actuated from the same source of power.

In the drawings:

Figure 1 is a plan view of my invention. 30 Fig. 2 shows the same in side elevation. Fig. 3 is a rear end view of the frame and material discharging devices. Fig. 4 is an enlarged view of the rear end of the machine. Fig. 5 is a similar view of the front 35 part thereof. Fig. 6 is a fragmentary detail of the bracket 18. Fig. 7 is an end view of the excavating blades. Figs. 8 and 9 show two different forms for said blades.

The frame of the machine consists of 40 lower beams 1 and upper beams 2, supported on the beams 1 by means of uprights 3. The frames thus formed are suitably united by cross-pieces in the usual manner. The lower part of the frame is supported on carrying-wheels 4. In the rear part of the frame is journaled a shaft 5, upon which is swingingly supported one end of a frame 6, so that the free end of such frame is capable 45 of vertical movement. In said free end of the frame is rotatably mounted a shaft 7, upon which is secured a cylindrical member 8, provided with radial plates 9, to which are attached blades 10, by means of bolts or similar fastening means permitting re- 50 moval of the blades for purposes of repair.

Fixed on the shaft 7 is a sprocket-wheel

11, connected by a sprocket-chain 12 with a similar wheel 13 on a shaft 14 journaled in the upper part of a pair of supports 15 attached to the frame 6. On the shaft 14 is 60 a pulley 16, to which movement may be imparted by a belt 17, connected with a suitable source of power ahead of the machine. Upon the shaft 14 being rotated, movement is communicated to the shaft 7 and excavating devices mounted thereon, to cause a rotation of said devices, so as to operate in the direction in which the machine is traveling. 65

Supported transversely of the upper part of the frame of the machine is a bracket 18, having a central threaded bearing 19 in which a screw 20 is adapted to operate, to lend vertical movement to said screw. The lower end of said screw is provided with a pivotal connection with the shaft 14, (not 70 shown) so that by the operation of such screw the shaft 14 and parts associated therewith, including the excavating devices, can be raised or lowered, at will. The upper end of the screw 20 is provided with a 75 hand-wheel 21, by means of which the same may be operated.

In rear of the shaft 7 there is supported from the frame 6 a roller 22, around which passes an endless apron 23, which is further supported in the rear part of the machine by a drum 24 on the shaft 5. The shaft 5 is actuated by means of a sprocket-wheel 25 fixed thereon, and connected by a sprocket-chain 26 with a similar wheel 27 90 on a shaft 28, rotatably mounted at one side of the frame. Power may be applied to the shaft 28, to suitably rotate the same, by means of a pulley 29 on said shaft, adapted to be actuated by a belt 30, from the herein- 95 before mentioned source of power. Through the operation of the shafts 28 and 5 the upper strip of the apron 23 is caused to travel upwardly and rearwardly.

At the rear end of the machine, on opposite sides thereof, are shafts 31 and 32, on which are fixed rollers 33, around which passes an endless carrier 34. On one end of the shaft 31 is a bevel-gear wheel 35, in mesh with a similar wheel 36 on the end of 100 the shaft 5. Movement of the shaft 5 is thus imparted to the shaft 31, to cause a continuous operation of the carrier 34, while 105 said shafts are in motion.

The blades 10 are bent in the direction 110 of their movement, and when such blades are in rotation, and in engagement with the

earth, they have a scooping or shoveling effect, and operate to throw the earth with which they come in contact in an upward and rearward direction, and upon the apron 5 23. The movement of said apron carries the material upwardly and rearwardly and dumps the same upon the carrier 34, by which it is moved to the side of the machine, and discharged upon the ground or into a 10 suitable conveyance for transportation. The cutting edges of the blades 10 may be on a straight line, as shown in Fig. 8, or the same can be serrated, as in Fig. 9. The blades can also be set in spiral form, if de- 15 sired.

In using the machine the frame 6 is gradually lowered, with the excavating devices in operation, until such devices cut a little ways into the ground. The machine 20 is then moved forward, and a layer of the earth removed by such devices and carried to one side of the machine. The operation is then repeated, with the excavating mechanism at a lower level, and this is repeated 25 until a trench is formed which possesses the required depth. The width of the trench is determined by the length of the blades 10.

Swingingly supported on the shaft 14 is a pair of arms 37, united by an arch member 30 38, with which the lower end of a screw 39 is rotatably connected, such screw passing upwardly through a threaded bearing in a bracket 40, supported from the side-pieces 2, said bracket being similar to the bracket 35 18 hereinbefore described. At its upper end the screw 39 is provided with a hand-wheel 41, and by the rotation of said screw the arms 37 can be raised or lowered, at will. In the free ends of the arms 37 is rotatably 40 mounted a shaft 42, on which is fixed a series of spaced-apart saw-tooth cutters 43. Movement is imparted to the shaft 42 by means of a sprocket-wheel 44 fixed thereon and connected by a chain 45 with a similar 45 wheel 46 on the shaft 14. The arms 37 are

held in proper operating position by means of arms 47, attached thereto and passing through loops 48 secured to the frame. Upon the shaft 14 being rotated the movement thereof will be communicated to the 50 shaft 42, causing a rotation thereof and of the cutters 43. When such cutters are in operation, and are brought into contact with the earth through the lowering of the arms 37, the earth will be cut and loosened thereby, so that it can be readily handled by the excavating devices. In many cases the ground would be sufficiently soft for the operation of the blades 10 alone, and it would not be necessary to use the cutting 55 devices, but when working in harder material, such as clay or other hard earth, it can first be prepared by the disks 43 for handling by the blades 10. When in use the cutting devices are on practically the 60 same level with the excavating mechanism, and a short distance in advance thereof.

The machine may be provided at its forward end with connecting rods 49, for attachment to the tractor or other motive 70 power by means of which the machine is operated.

What I claim and desire to secure, is:

A device of the class described, comprising a main portable frame; a pair of auxiliary frames supported in said main frame so as to be capable of vertical adjustment therein, independently of each other, one of said auxiliary frames being in advance of the other; an excavating cylinder carried by the rear one of said frames, provided with a plurality of transverse blades; a series of spaced-apart serrated disks rotatably supported by the forward frame; and conveying mechanism adapted to receive material 75 from said excavating cylinder and discharge it at the side of the machine. 80 85

In testimony whereof I affix my signature.

E ANDERS CHATTSTROM.
